UNITED STATES PATENT OFFICE.

CHARLES P. KUEHN, OF CHICAGO, ILLINOIS, ASSIGNOR TO A. STEIN & COMPANY, OF CHICAGO, ILLINOIS, A CORPORATION.

DESIGN FOR AN ARMBAND-CLASP.

48,250.

Specification for Design.

Patented Dec. 7, 1915.

Application filed January 4, 1915. Serial No. 530. Term of patent 7 years.

To all whom it may concern:

Be it known that I, CHARLES P. KUEHN, a citizen of the United States, and a resident of Chicago, county of Cook, and State of Illinois, have invented a new, original, and ornamental Design for Armband-Clasps, of which the following is a specification, reference being had to the accompanying drawing, forming part thereof.

The figure is a perspective view, the arm band being shown in dotted lines.

I claim:

The ornamental design for an arm band clasp as shown.

CHARLES P. KUEHN.

Witnesses:

GEORGE P. FISHER,
GEO. F. FISHER.
